UNITED STATES PATENT OFFICE

96,377

DESIGN FOR A TEXTILE FABRIC

Curt Erwin Forstmann, Montclair, N. J.

Application March 13, 1935, Serial No. 55,877

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure is a plan view of a piece of the textile fabric embodying the design of the present invention.

The area included between the dot and dash lines indicates the repeated design unit.

The design comprises stripes on a plain back-

ground, the stripes being each delineated by several pairs of parallel loosely woven "flame" yarns, that is to say, unevenly spun yarns having nodes or swells at intervals, yarns of the pairs being spaced at different widths, the background between the stripes being relieved by single lines of loosely woven "flame" yarns, and the fabric being sparsely overcast with diagonal shoots, which, intersecting the stripes, give them a chain-like tracery.

I claim:

The ornamental design for textile fabric as shown and described.

CURT ERWIN FORSTMANN.
